FUR CARROTING MACHINE

William Lewis Braun, Norwalk, Conn., assignor, by mesne assignments, to Carrotting Machine & Chemicals Co., Inc., Newark, N. J., a corporation of New Jersey

Application February 20, 1946, Serial No. 649,019

19 Claims. (Cl. 69—28)

This invention relates to a machine for car-rotting fur, particularly to a machine for car-rotting fur on the skin as one of the steps for preparing fur for felting in making hats, and has for an object to provide a machine which will take the place of the hand carrotting operation now generally employed which is dangerous to the health of the operator because of the solutions used.

Another object is to provide a machine which will more uniformly and effectively apply the carrotting solution to the fur on the skin than can be done with the hand operation, and also to reduce the amount of carrotting solution required for carrotting a given number of skins.

A further object is to provide a construction in which the means for supporting and feeding the skins are so mounted that they may be raised with the brushes for applying the carrotting solution to the fur, so that the brushes may be readily inspected and also easily and quickly removed and replaced.

A further object is to provide a construction and arrangement in which, in addition to the advantages stated, the operators are protected not only from contact with the solution itself, but also the fumes from the solution.

With the foregoing and other objects in view, I have devised the construction illustrated in the accompanying drawings forming a part of this specification. It is, however, to be understood the invention is not limited to the specific details of construction and arrangement shown, but may embody various changes and modifications within the scope of the invention.

In these drawings:

Fig. 1 is a partial side elevation and partial section of the machine;

Fig. 2 is a top plan view thereof with certain portions broken away to more clearly show the construction;

Fig. 3 is a transverse section substantially on line 3—3 of Fig. 4, but showing the end of the endless conveyor mechanism in elevation;

Fig. 4 is a longitudinal section of the device showing the endless conveyor in elevation;

Fig. 5 is a side view of one end of one form of endless conveyor and operating sprocket therefor the shaft being omitted;

Fig. 6 is a detail of the construction of Fig. 5;

Fig. 7 is an end view of the construction of Fig. 5;

Fig. 8 is a view similar to Fig. 5 showing a modified construction;

Fig. 9 is an end view of one means of mounting the brushes;

Fig. 10 is a transverse section thereof, substantially on the line 10—10 of Fig. 9;

Fig. 11 is a plan view of a portion of the means for supporting the skins;

Fig. 12 is an end view thereof;

Fig. 13 is a detail section showing a means for mounting and supporting the pelt supporting wires, and

Fig. 14 is an end elevation thereof.

The machine shown comprises a supporting frame 1 of any suitable construction including upright legs or supports 2 of angle members and connecting longitudinal angle members 3 and transverse bars 3a.

Pivotedly mounted on this main frame is a second frame 4, of any suitable construction but in the present case comprising spaced side members 5 of angle bar construction connected by transverse end members 6 and transverse angle bars 7. This whole frame is pivoted to the first frame 1 intermediate its length by means of the hinge pins 8 through suitable bearings 9 mounted on the frame 1 and brackets 10 secured to the side members of the frame 4.

Mounted on the upper frame 4 is means for supporting the skins and feeding them through the machine during the carrotting operation. This comprises a series of longitudinal wires 11 supported at their opposite ends on suitable transverse bars 12 and 13 extending between and supported by the side members 5, and these wires are mounted by means so that they may be kept taut. They are preferably of stainless steel construction so as to resist the action of the carrotting solution. They are firmly anchored to the bar 12 and anchored to the bar 13 by adjusting means to keep them taut, as shown in Figs. 13 and 14. The arrangement shown comprises a pin 14 rotatable in the bar 13, one for each wire, and to which the end of the wire is connected. The pin may be rotated to adjust the tightness of the wire by a suitable rod or key inserted in the opening 15 in the pin, and then the pin secured in adjusted position by a suitable holding means, such as the set screw 16. This bar 13 may also be secured to the transverse angle bar 7, as indicated at 17, so as to further support this bar.

Located immediately above the supporting wires for the skins is a means for gripping the skins and feeding them longitudinally along the wires during the carrotting operation. The skins

are fed into the machine from the right hand end as viewed in Figs. 1 and 4 from the feed table 18 and are fed in the direction indicated by the arrow 19 and discharged at the rear or left hand end of the machine into any suitable container (not shown). The preferred form of conveyor and feeding device comprises an endless chain conveyor 20 arranged with the lower run 21 immediately above the wires 11, and it comprises a pair of flexible chains 22 running over suitable sprockets 23 and 24 arranged at the opposite ends of the supporting wires and supported on suitable cross shafts 25 and 26 respectively, mounted in suitable bearings 27 supported on the side members 5 of the upper frame. The shaft 25 and the sprocket 23 are driven from any suitable means to drive the conveyor, such, for example, as the sprocket 28 driven by a suitable chain drive 29 from the reducing gear drive 30 from the electric motor 31.

The feed conveyor may be of different constructions, that shown in Figs. 1 to 5 comprising the two spaced chains 22 of pivotally connected links 32 and 33 (Fig. 5) of the general type of bicycle chain, and to alternate links of the two chains are secured cross bars 34 having a series of pins 35 to pierce the skin of the pelt the fur of which is being carotted, so as to form a positive grip on the pelt or skin to feed it along the wires 11 during the carrottting operation. These bars are preferably of some material which is highly resistant to the chemical action of the carrottting solution, such, for example, as stainless steel. In the form shown in these figures there is a series of bars 36 positioned on edge and mounted in recesses in discs or plates 37 mounted on the rear shaft 25 between the sprockets 23, as shown more clearly in Figs. 5 and 7. These bars are so arranged that as the conveyor passes around these sprockets the bars 36 come between the bars 34 and they project sufficiently above the edge of the disc, as shown in Fig. 5 (about equal to the projection of the points or pins 35 has been found satisfactory), so that as the skin 38 reaches these sprockets after the carrottting operation these bars 36, as shown in Fig. 5, will engage the skin 38 between two bars 34 and will push the skin downwardly off the pins 35 so as to disconnect it from these pins and prevent its being carried around these sprockets with the conveyor. The skin may drop onto an endless rubber or canvas belt 39 and be deposited by this belt at the rear end of the machine. This canvas or rubber belt may run over a pair of rollers 40 one of which, such as the rear roller, may be operated from the reducing drive 30 through a suitable belt 41.

As the thickness of the fur may vary for different pelts or skins, and also as, when the skin is on the supporting wires 11 they may tend to lift the lower run 21 of the conveyor, supports or back-up means for this lower run are provided immediately above it. These comprise a series of longitudinal bars 42 placed on edge immediately above this lower run and supported by any suitable means, such as the transverse angle bars 43 supported on the side frame. It will be clear that these bars 42 hold the lower run 21 of the conveyor down in proper position so as to force the points 35 into the skin and they also prevent the pelt from being raised by the pressure of the carrott applying brushes. In other words, they hold the pelt in the proper position with respect to the brushes and prevent their moving away under pressure of the brushes, and thus assure that the

carrot is properly applied to the fur, and also brushed or rubbed into it.

These brushes are rotary brushes, indicated at 44, 45 and 46. The number may vary, but three brushes have been found to be very satisfactory. They may also be driven to move in different directions with respect to the lay of the fur on the skin as is found to be most desirable for the skins being treated, but as shown on the drawing, the first brush 44 is arranged to rotate in the direction of the lay of the fur when the skin or pelt is fed tail first to the machine. The second brush 45 rotates in the opposite direction or against the lay of the fur to rub the solution into the fur, while the third brush 46 is located to the rear of the first two brushes and rotates in the direction of the lay of the fur so as to slick this fur and lay it down and also remove surplus carrottting solution from the fur. These brushes are all cylindrical brushes mounted to rotate at proper speed, it being preferred that the first brush 44 be the slowest and driven at a speed of about 72 R. P. M., the second brush 45 being rotated at an intermediate speed of about 110 R. P. M., and the third or slicking brush 46 be operated at a higher speed of, for example, about 130 R. P. M., with the brushes about four inches in diameter. It is also preferred that the sprockets 23 of the conveyor 20 be operated at about 40 R. P. M., so that the conveyor makes about 6½ complete revolutions per minute. The device is, however, not limited to these particular speeds, as they may vary as found desirable to suit different conditions or different types of fur.

The three brushes are all mounted in the upper frame 4, so that when the upper frame 4 is tipped upwardly, as indicated in dotted lines Fig. 1, the feed conveyor 20 and the pelt supporting wires 11 will be raised with the brushes, thus leaving the brushes uncovered and clear for easy inspection and easy removal or mounting in place. This permits mounting or dismounting of the brushes for cleaning, renewal, or repair without the necessity of breaking down the machine. All that is necessary is to lift the front end or depress the rear end of the upper frame 4. This also exposes the supporting wires 11 and the associated parts, including the lower run of the feed conveyor, for ready inspection, cleaning, and repair. The brushes are mounted on suitable transverse shafts 47 running in suitable bearings mounted on the side members of the upper frame 4, and they are preferably mounted so as to be adjustable, as shown in Figs. 9 and 10, to vary the position of the brushes with respect to the supporting wires 11 and therefore the skin or pelt being operated upon.

The mounting shown in Figs. 9 and 10 is a simple and effective one, permitting easy adjustment of the brushes, and also permitting easy dismounting and removal of an old brush and its replacement by a new one. The bearing shown comprises upright spaced guide blocks 49 between which is mounted the ball bearing 50 for the shaft 47, there being guide plates 51 on the opposite sides engaging the opposite sides of the guide 49 to retain the bearing between the guides 49, and these plates may be connected by any suitable transverse bolts 52. A substantially U-shaped block 53 is secured to the bottom of the bearing and supported on an adjusting screw 54 mounted in a strap 55 secured to the lower ends of the guides 49 by any suitable means, such as the screws 56. It will be understood that the

bearing may be easily removed by removing the screws 56.

The carotting solution is applied by the brushes 44 and 45, and for this purpose these brushes are mounted in a container or pan 57 for this carotting solution 58, and as will be seen from Fig. 4, the level of this solution is maintained in this pan at a height so that the lower portion of the brushes is immersed in this material so as to pick it up and carry it to the fur on the skin and apply and brush it into this fur. Means is provided for automatically maintaining the level of this solution constant and at the proper level for most effective operation. This is shown in Figs. 2 and 3, and comprises a supply tank 59 at one side of the machine to hold a supply of the carotting solution and is connected by a pipe 60 through a control valve 61 with a float tank 62, the tank 59 being located higher than the tank 62 so that the solution flows to the latter by gravity. In the discharge end of the pipe 60 in the tank 62 is a valve 63 controlled by a suitable float 64, thus maintaining the level of liquid in the tank 62 constant, and this tank communicates with the pan or container 57 through the conduit or pipe 65 at the desired level to be maintained in the pan 57. An overflow pipe 66 leads from the tank 62 to the overflow tray or pan 67, so that should the float valve fail, the main supply tank 57 will not be flooded. The overflow pan 67 encloses the pan 57 and also surrounds it on the sides and ends, so that liquid splashed from the tank 57 will be caught and collected. It will also be seen from Fig. 4 that the final or slicking brush 46 is not located in the pan 57, but is outside this pan in the pan 67, so that the surplus carotting solution brushed from the fur by the brush 46 is caught by this pan 67 and recovered by being carried to any suitable container (not shown) through a drain-out pipe 68, and there may also be a clean-out or drain outlet 69 in the bottom of the pan 57 through which the solution in this pan may be drained if desired, this opening being normally closed by a suitable closure or plug 70. The sides of the tanks 57 and 67 are preferably carried up to a position just under the skin supporting wires 11, as shown in Fig. 4, so as to prevent splash from the brushes being thrown outside and insuring that it is all collected. As the brushes are mounted in the tanks or trays, these side walls are provided with slots 71 leading from the upper edges of these walls to receive the shaft 47 of the brushes and permit them to be lowered to their proper positions.

The forward ends of the side members 5 of the upper frame 4 are extended forwardly beyond the front ends of the conveyor 20, as shown in Figs. 1 and 2, and mounted on them is a feed table 18 on which the skins or pelts may be spread out and flattened before feeding them to the machine. The rear ends of these side members are projected beyond the rear end of the conveyor 20 to carry the receiving conveyor 39, or they could be covered with a plate forming a receiving table. The rear cross member 6 is provided with compartments in which is placed lead or other suitable material 72 to counterbalance the forward portion of this frame and the parts carried thereby, and if desired an additional counterweight 72a, so that very little lifting is required in tipping the frame to the dotted line position of Fig. 1. There are, of course, suitable controls for the motor 31, such, for example, as the control switch 73 in power supply leads 74. There may also be a feed guide roller 15 at the rear of the feed table 18

and just in front of the entrance to the feed conveyor 20 to guide the pelts being fed onto the supporting wires 11 between these wires and the feed conveyor 20. The upper frame 4 is secured in the operative position by any suitable catch means, such, for example, as the pivoted catch bolts 16, one on each side, pivoted to the upper frame at 77, and at its lower end adapted to seat between a pair of lugs 78 on the lower frame and secured by a hand operable clamping nut 79.

The three brushes 44, 45 and 46 are driven by the drive motor 31, and in the arrangement shown they are driven from an enlarged sprocket 80 on the rear conveyor shaft 25, and on each of the shafts 47 of the respective brushes are sprockets 81 for brush 44, 82 for brush 45, and 83 for brush 46. All of these elements are mounted on the hinged frame and move with it. As they are all driven by the same chain 84 from the sprocket 80, these sprockets are of different sizes depending on the speed desired for each individual brush, as will be apparent. At the forward end the chain runs over upper and lower idler guide sprockets 85 and 85' mounted on a depending bar 85" secured to the pivoted frame and at the rear and below the sprocket 80 over another idler 86. This latter sprocket, however, is preferably mounted on a pivoted lever 87 mounted on the motor support 30' by the bolt 87', to which lever 87 is secured a spring 88 tending to swing the sprocket downwardly and thus maintain the chain 84 at the proper tension. As motor support 30' is on and moves with the pivoted frame sprocket 86 will also move with this frame.

As the thickness of the fur on the pelt varies, it being thicker at locations near and on opposite sides of the center of the back, and therefore because of this greater thickness it would tend to apply greater pressure to the supporting wires at these points, it is preferred to locate the wires closer together at these points of greater thickness of fur, as indicated in Fig. 2 and 14, where it will be seen that the wires 20a and 20b are located closer together and therefore provide greater support than the intermediate wires 20 which are spaced farther apart.

In Fig. 8 is shown a modified construction of the feed conveyor 20. Here on the links 22 are mounted wider plates or bars 88 than are the bars 34, and they are arranged on every other link 22 with the forward edge 89 at the forward edge of the securing lug 90 on the chain link and its opposite or rear edge is carried back to a position just in front of the forward edge of the next following plate or bar 88. The driving pins or points 92 corresponding to the points 35 which engage the skin of the pelt, as previously described, are located just behind the forward edge 89, as shown. With this construction, as the conveyor and the chain run around the rear sprocket 28, the rear edge of plate or bar 88 will be swung out at an angle, as indicated at 88a in Fig. 8, and because the rear edge of this bar or plate extends considerably to the rear of the link 22 on which it is mounted, this rear edge will be swung downwardly a considerable distance below the forward edge of the next following bar or plate 88b, and therefore it will be seen that this rear edge 89 of the plate 88a will force the skin 38 of the pelt downwardly and loosen it from the pins 92 of the next following bar 88b. This insures that the skin or pelt is effectively loosened and disconnected from the pins of the feed conveyor, so that there is no danger of its being carried around the sprockets 28 by the conveyor.

The portion of the machine including the feed conveyor 20 and associated parts may be enclosed in a suitable hood 93 placed over them to collect any fumes or carroting solution which may be thrown up by the brushes, and the fumes may be carried off through any suitable ventilating connection 94, and access may be had to the feed conveyor and other parts by merely lifting the hood. Any suitable hood may be used as it is used merely to collect fumes from the machine so they may be carried away by a fan or other suitable means. The hood may merely rest on suitable supports on the machine so as to be lifted and placed to one side when access is desired to the machine or it is desired to raise the upper frame 4; 15 or if preferred it could be mounted on suitable raising and lowering means.

It will be evident from the above that the device is so arranged that the parts are all easily accessible for inspection, cleaning, renewal or repair. An especially desirable feature is the arrangement of the supporting means for skin and the feed means on the upper frame which may be raised from the lower frame carrying the pans or containers for the carroting solution. This makes it possible to renew and remove the brushes without breaking down the whole machine or removing a whole lot of parts, such as the skin supporting means, conveyor and so forth, greatly reducing the time lost in renewing the brushes or making inspections or repairs. This machine carrots the skins much more rapidly than can be done by the old hand method, and furthermore, applies the carroting solution much more evenly and uniformly to the fur, and effects a saving in the amount of carroting solution used because of this more uniform application and also because it obviates the splashing and loss of the carroting solution which is caused by the dipping and carrying of the hand brushes from the pan containing the solution to the skins. It also prevents splashing of the carroting solution on the garments or the skin of the operators and is a protection to the health of the operators because the fumes escaping into the surrounding atmosphere are greatly reduced.

Also with this machine it is possible to use lower concentrations of carroting solutions, as the solution is much more thoroughly and evenly worked into the fur than is possible by the conventional hand method.

On the other hand it is also possible to use much higher concentrations of carroting solutions, as it is possible to so adjust the machine as to make lighter applications and it is more evenly applied, and because the machine is covered and all the fumes taken away there is no danger affecting the health of men as would be the case if solutions of such concentrations were applied by hand.

Having thus set forth the nature of my invention, I claim:

1. A fur carroting machine comprising a supporting frame, a second frame pivoted to the first frame to swing about a horizontal axis, a series of longitudinal wires mounted on the second frame to support a skin with the fur side down, means on the upper side of said wires to grip the skin and feed it along the wires, a plurality of rotary brushes mounted immediately under the wires to brush the fur on the skin, a container for carroting solution mounted in the first frame below at least one of the brushes and arranged so that the lower portion of the brush is immersed in the solution to carry it to the fur, another of

5 said brushes acting as a slicking brush to remove surplus solution from the fur, and said pivot for the second frame being so arranged that tilting of this frame will raise the wires and feed means from the lower frame whereby the parts carried by both frames are accessible for inspection and repair.

2. A fur carroting machine comprising a lower supporting frame and an upper frame pivoted to the lower frame to swing about a horizontal axis to permit lifting of said frame from the lower frame, means on the upper frame to support a skin with the fur side down and exposed from beneath and for feeding the skin horizontally, a series of rotary brushes mounted beneath the skin supporting and feeding means, and means for supplying carroting solution to at least one of the brushes for application by the brush to the fur.

3. A fur carroting machine comprising a lower supporting frame, an upper frame hinged to the lower frame to swing about a horizontal axis, a series of horizontal supporting wires mounted in and extending longitudinally of the upper frame, 25 said wires being adapted to support a pelt with the fur side down, an endless conveyor mounted above said wires provided with pins to grip the skin to feed it along said wires, rotary brushes mounted beneath said wires, a container in the lower frame for supplying carroting solution to at least one of the brushes for application to the fur, and said hinged connection being so arranged that the wires and feeding means may be lifted by tilting the upper frame.

35 4. A fur carroting machine comprising a lower supporting frame, an upper frame hinged to the lower frame to swing about a horizontal axis, a series of horizontal supporting wires mounted in and extending longitudinally of the upper frame, 40 said wires being adapted to support a pelt with the fur side down, means mounted above the wires to grip the pelt and feed it along said wires, rotary brushes mounted beneath said wires, a container for carroting solution mounted in the lower frame, at least one of said brushes being mounted in said container so that it is immersed 45 in the solution and carries it to the fur, means for driving the brushes to brush the solution into the fur, and said hinge connection being so arranged that tilting the upper frame will lift the wires and feeding means.

55 5. A fur carroting machine comprising a lower supporting frame, an upper frame hinged to the lower frame to swing about a horizontal axis, a series of horizontal supporting wires mounted in and extending longitudinally of the upper frame, 60 said wires being adapted to support a pelt with the fur side down, means mounted above the wires to grip the pelt and feed it along the wires, a container for carroting solution mounted in the lower frame, an overflow pan enclosing and spaced from the first container, said container and pan being located immediately under said wires, a series of rotary brushes under said wires, 65 at least one brush being located in said container and so located as to be immersed at its lower side in said solution and apply it to the fur, another brush being located outside the container and in the overflow pan to brush surplus solution from 70 the fur, and said hinged connection being so located that tipping of the upper frame will lift the wires and feeding means with the brushes from said container and pan.

6. A fur carroting machine comprising a series 75 of longitudinal wires for supporting a pelt with

the fur side down, means above the wires for gripping the pelt and feeding it along the wires, rotary brushes beneath the wires to apply carroting solution to the fur and brush it, and said wires being arranged in spaced groups of wires located closer together than the wires between the groups to provide greater support for portions of the pelt having the heavier thicker fur.

7. A fur carroting machine comprising a series of longitudinal wires for supporting a pelt with the fur side down, means above the wires for gripping the pelt and feeding it along the wires comprising an endless conveyor including a pair of laterally spaced chains running over sprockets, a series of transverse bars mounted on said chains, means on said bars to grip the skin of the pelt, rotary brushes under the wires, positioned to apply carroting solution to the fur, and a series of longitudinally extending bars mounted immediately above the bars of the lower run of said conveyor to hold said bars down on the skin and prevent their being lifted by pressure of the pelt and brushes.

8. A fur carroting machine comprising a lower supporting frame, an upper frame hinged to the lower frame to swing about a horizontal axis, a series of horizontal supporting wires mounted in and extending longitudinally of the upper frame, said wires being adapted to support a pelt with the fur side down, means mounted above the wires in the upper frame to grip the pelt and feed it along the wires, an overflow pan mounted in the first frame below the wires, a container for carroting solution mounted in and enclosed by said pan, rotary brushes mounted below the wires in said pan and container to apply solution to the fur, said brushes being mounted on shafts, bearings for the shafts mounted in upright guides, and means for shifting the bearings in said guides to adjust the position of the brushes with respect to said wires.

9. A fur carroting machine comprising a series of horizontal wires to carry a skin with the fur side down, means above the wires to feed the skin along the wires comprising an endless conveyor including laterally spaced chains running over sprockets on longitudinally spaced shafts at the entrance and exit ends of the conveyor, a series of spaced transverse bars secured to the chains, pins on the bars extending downwardly therefrom when in the lower run of the conveyor to grip the skin on the wires to feed it along the wires, and a series of longitudinal bars mounted on the shaft at the outlet end of the conveyor between the chain sprockets, said bars being spaced so as to be located between the transverse bars of the conveyor as they pass around the sprockets, and said bars on the shaft extending beyond the outer surfaces of the conveyor bars sufficiently to remove the skin from the pins as they pass over the sprockets.

10. A fur carroting machine comprising a series of horizontal wires to carry a skin with the fur side down, means above the wires to feed the skin along the wires comprising an endless conveyor including laterally spaced chains running over sprockets on shafts at opposite ends of the conveyor, transverse flat bars secured to alternate links of the chain, each bar when on the lower run of the conveyor being secured at its forward edge portion to said links and of a width so that its rear edge is adjacent the forward edge of the next adjacent following link, and pins on the bars adjacent their forward edges adapted to grip a skin to feed it along the wires and so arranged

that as the bars pass around the sprockets at the exit end of the conveyor the rear edge of each bar will be swung outwardly to remove the skin from the pins of the next following bar.

5. 11. A fur carroting machine comprising a series of wires to support a pelt with the fur side down, brushes under the wires for applying carroting solution to the fur, means above the wires for feeding the pelt along the wires comprising an endless conveyor running over sprockets at its opposite ends and including a series of transverse bars provided with downwardly projecting pins when on the lower run to grip the skin of the pelt, and means moving with the conveyor and operating by movement of the conveyor around the sprockets at its discharge end to force the skin from the pins.
10. 12. A fur carroting machine comprising a series of wires to support a pelt with the fur side down, brushes under the wires for applying carroting solution to the fur, means above the wires for feeding the pelt along the wires comprising an endless conveyor including laterally spaced chains running over sprockets at opposite ends of the conveyor, a series of transverse bars secured to links of the chains and provided with outwardly extending pins to grip the skin of the pelt, and said pins being so arranged and the width of the bars being such that as the bars swing out of the plane of the lower run in going around the sprockets at the discharge end of the conveyor, the movement of a bar to an angular position forces the skin from the pins of the adjacent bar.
15. 13. A fur carroting machine comprising a lower supporting frame and an upper frame pivoted to the lower frame to swing about a horizontal axis to permit lifting of said frame from the lower frame, means on the upper frame to support a skin with the fur side down and exposed from beneath and for feeding the skin horizontally, a series of rotary brushes mounted in the upper frame beneath the skin supporting and feeding means to swing with this frame, and means for supplying carroting solution to at least one of the brushes for application by the brush to the fur.
20. 14. A fur carroting machine comprising a lower supporting frame, an upper frame hinged to the lower frame to swing about a horizontal axis, a series of horizontal supporting wires mounted in and extending longitudinally of the upper frame, said wires being adapted to support a pelt with the fur side down, an endless conveyor mounted above said wires provided with pins to grip the skin to feed it along said wires, rotary brushes mounted in the upper frame beneath said wires, a container in the lower frame for supplying carroting solution to at least one of the brushes for application to the fur, and said hinged connection being so arranged that the wires, feeding means and brushes may be lifted by tilting the upper frame.
25. 15. A fur carroting machine comprising a lower supporting frame, an upper frame hinged to the lower frame to swing about a horizontal axis, a series of horizontal supporting wires mounted in and extending longitudinally of the upper frame, said wires being adapted to support a pelt with the fur side down, means mounted above the wires to grip the pelt and feed it along said wires, rotary brushes mounted in the upper frame beneath said wires, a container for carroting solution mounted in the lower frame, at least one 30 of said brushes being mounted in said container

so that its lower portion is immersed in the solution and carries it to the fur, means for driving the brushes to brush the solution into the fur, and said hinge connection being so arranged that tilting the upper frame will lift the wires, feeding means and brushes.

16. A fur carroting machine comprising a supporting frame, a second frame pivoted to the first frame to swing about a horizontal axis, a series of longitudinal wires mounted on the second frame to support a skin with the fur side down, means on the upper side of said wires to grip the skin and feed it along the wires, a plurality of rotary brushes mounted in the second frame immediately under the wires to brush the fur on the skin, a container for carroting solution mounted in the first frame below at least one of the brushes and arranged so that the lower portion of the brush is immersed in the solution to carry it to the fur, another of said brushes acting as aslicking brush to remove surplus solution from the fur, and said pivot for the second frame being so arranged that tilting of this frame will raise the wires, feed means and brushes from the lower frame whereby the parts carried by both frames are accessible for inspection, cleaning and repair.

17. A fur carroting machine comprising a series of longitudinal wires for supporting a pelt with the fur side down, means above the wires for gripping the pelt to hold it against the wires and feed it longitudinally along the wires, a container for carroting solution mounted under the wires, an overflow pan enclosing and spaced from the container, said container and pan being located immediately under the wires, a plurality of rotary brushes under said wires, at least one brush being located in said container and so located as to be immersed at its lower side in said solution and apply it to the fur as the pelt is fed along the wires, and another brush being located outside the container and in the overflow pan to brush surplus solution from the fur.

18. A fur carroting machine comprising a series of longitudinal wires adapted to support a pelt with the fur side down, means mounted above the wires to grip the pelt and feed it longitudinally along the wires, an overflow pan mounted imme-

dately below the wires, a container for carroting solution mounted in and enclosed by said pan, the pan and container each including side walls extending upwardly to a position adjacent the wires, and a plurality of rotary brushes mounted below the wires, at least one brush being mounted in the container to apply carroting solution from the container to the fur as the pelt is fed along the wires, and another brush being located in the pan outside the container to brush surplus solution from the fur.

19. A fur carroting machine comprising a lower supporting frame and an upper frame pivoted to the lower frame to swing about a horizontal axis to permit lifting of said upper frame from the lower frame, a series of spaced longitudinal supporting wires mounted in the upper frame arranged to carry a skin with the fur side down, means located at the upper side of the wires to grip the skin to hold it on the wires and to feed it longitudinally along the wires, a plurality of rotary brushes mounted in the upper frame immediately under the wires to brush the fur on the skin as it is fed along the wires, means mounting the brushes arranged to adjust the brushes toward and from the wires to control the position of the brushes with respect to the fur being brushed, a container for carroting solution mounted in the lower frame below the wires, at least one of the brushes being mounted in the container to carry the solution to the fur as the skin is fed along the wires, and another brush being arranged to brush surplus solution from the fur.
